UNITED STATES PATENT OFFICE.

WILLIAM J. BOHAN, OF ST. PAUL, MINNESOTA.

ELECTRICAL SWITCH-ACTUATING MECHANISM.

1,157,076.

Specification of Letters Patent.

Patented Oct. 19, 1915.

Application filed August 3, 1914. Serial No. 854,718.

To all whom it may concern:

Be it known that I, WILLIAM J. BOHAN, a citizen of the United States, residing at St. Paul, in the county of Ramsey and State of Minnesota, have invented certain new and useful Improvements in Electrical Switch-Actuating Mechanism; and I do hereby declare the following to be a full, clear, and exact description of the invention, such as 10 will enable others skilled in the art to which it appertains to make and use the same.

My invention has for its object to provide an improved electric switch actuating mechanism for railways, and to such ends, generally stated, the invention consists of the novel devices and combinations of devices hereinafter described and defined in the claims.

More specifically stated, the invention has 20 for its object to provide a switch actuating mechanism which is operable from an engine cab, or other part of the train, and whereby the switch may be thrown without stopping of the train and without depending upon operation from a tower or other locality than the train itself.

Also, the invention provides means whereby, when the train has passed the switch into a position clearing the main line, the said 30 switch will be automatically thrown back to its normal or main line position.

As a highly important feature, the invention includes a motor which is arranged to run in one or a constant direction, to impart 35 both movements to the switch, to-wit, both the main line opening and main line closing movements. Such a motor necessitates the use of an eccentric crank or other "to and fro" motion device, whereby the motor running in one, or a constant direction, will, in 40 succession, impart the two above noted movements to the switch. This feature eliminates all pole changing mechanisms with their usual complications.

In applying the invention, the rails of 45 the main line and side track or branch line are provided with the insulated track sections and source of electrical energy, and I further provide an associated motor circuit 50 including an electric switch called the circuit selector, and provide on the engine, or other suitable part of the train, a trolley or circuit closer by means of which a certain properly disposed section of the said motor 55 circuit, termed trolley lines, may be electrically connected at will, while the train is in motion.

With the above general statements in mind, the details of the preferred arrangement of the invention will be understood 60 from the accompanying drawings and following detailed description.

In the drawings, like characters indicate like parts throughout the several views.

Referring to the drawings: Figure 1 is a 65 diagrammatic plan view illustrating the system, including the switch actuating circuit and mechanism; Fig. 2 is a diagrammatic end elevation of the locomotive and a portion of the switch actuating circuit; 70 Fig. 3 is a plan view showing portions of the main line and side track and switch actuating mechanism; Fig. 4 is a plan view with some parts broken away, showing a portion of the track, the switch actuated 75 motor and connections between the latter and the connecting rod; Fig. 5 is a section taken approximately on the line $x^5 x^5$ on Fig. 4, and showing also a casing for inclosing the motor and certain of the parts; 80 and Fig. 6 is an enlarged section taken approximately on the line $x^6 x^6$ on Fig. 4.

The numerals 1 and 2 indicate the rails 85 of the main line and side track, respectively, and the numeral 3 indicates the switch rod for throwing the movable rails of the switch in the customary way. The switch rod 3, while connected to the ends of the split rails, is electrically insulated therefrom. The projecting end of the switch rod 3, in the 90 construction illustrated, is connected by a rod 4 to a lever 5 intermediately pivoted to a suitable fixed bearing 6, with its short end connected by an eccentric rod 7 to an eccentric 8, which, as shown, is on the hub 95 of a large worm gear 9 journaled on a heavy stud 10 of a fixed bearing plate 11. The eccentric 8 is, of course, the well known equivalent of a crank. Such eccentric or crank, in some arrangements, might be connected to the switch rod 3 direct, but the intermediate motion multiplying lever 5 is preferred because it reduces the required throw of the said eccentric or crank.

The worm gear 8 is engaged by a worm 105 12 of a shaft 13 mounted in suitable fixed bearings 14 and provided at one end, as shown, with a spur gear 15, which, in turn, meshes with a spur pinion 16 on the armature shaft of an electric switch operating 110 motor 17. As shown, the motor 17 and certain other of the switch operating connections are inclosed in a fixed casing 18, and the armature shaft of the motor, at one end,

projects through this casing and terminates in an angular shank 17^a, to which a hand operated crank may be attached to operate the switch by hand, in case there should be 5 a failure in the operation of the electric switch actuating mechanism.

For controlling the motor, I provide an electric circuit selector of novel construction, and which, as shown, comprises a continuous contact ring 19 and a sectional diametrically divided contact ring 20. Both of these contact rings are suitably fixed immediately below the worm 9, and the said worm gear carries a contact brush 21 that runs upon both of the said contact rings 19 and 20. The contact brush 21 is of sufficient width to span the gap between the ends of the sections of the divided contact ring 20. The main line rails are divided and insulated at 22, 23 and 23^a, and the side track rails are divided and insulated at 24.

The numeral 25 indicates a battery or other source of electrical energy which is connected across the main line rails, close to 25 the track insulations 22 on the switch side thereof.

The numeral 26 indicates a magnet which is electrically connected across the side track rails close to the insulations 24 on the switch side thereof. The main line rails are electrically connected with the branch line rails, as indicated, at 1^a and 1^b.

The numeral 27 indicates trolley wires or rails which run parallel to the main line rails from points in the vicinity of the track insulations 22, a prescribed distance toward the switch. One of these trolley wires 27 is connected, by a lead 28, to one side of the motor 17, and to a contact lever 29 that is 30 subject to the magnet 26. The other trolley wire 27 is connected by a lead 30 to one of the sections of the divided contact ring 20. The other section of the said divided contact ring 20 is connected by a lead 31 to a fixed 40 contact 32 with which the contact lever 29 is engaged when, and only when, the magnet 26 is energized. The continuous contact ring 19 is connected by a lead 33 to the motor 17, and, as shown, a battery or other source of 50 electrical energy 34 is interposed in the said lead 33. The so-called trolley wires or rails 27 may be supported in various different ways, but are preferably supported overhead or at the side of the track where they will 55 be free from tampering and where they may be engaged by a suitable trolley carried on the engine cab. Hence, as shown, in Fig. 2, the numeral 34 indicates one of several trolley poles used to support the said trolley lines 27.

In Fig. 2, the engine cab is diagrammatically indicated as an entirety by the numeral 35, and the trolley carried thereby, which is preferably of the pantagraph type, is diagrammatically indicated as an entirety by 65

the numeral 36. This trolley may take various different forms, so far as this invention is concerned, but it should be of a form adapted to be projected at will, so as to engage the two trolley lines 27 and close the 70 circuit between the same, while the engine or train is in motion, and during a period covering a sufficient time to operate the switch.

Operation: The diagrammatic view in Fig. 75

1 shows the normal condition of the switch actuating mechanism at which time, of course, the switch is set for the main line operation. At this time, the circuit from the battery 25 is closed through the magnet 26 and contact switch 29 is held against the contact 32. The lead wire 31 from the said contact 32 is connected to that section of the divided contact ring 20 which is then electrically disconnected from the motor 17 and battery 34, for the reason that the movable contact brush 21 is then engaged with the opposite section of the said divided contact ring 20 and also, of course, with the fixed contact ring 19. Hence, at this time, the circuit from the latter noted section of the said ring 20, through the motor 17 and battery 34, is opened only between the trolley lines 80

27. Hence, the system is now in such condition that when the locomotive moves on the main line from right toward the left, in respect to Fig. 1, toward the switch and past the track insulations 22, the following operations will take place, to-wit: If the trolley 85

36 be projected into contact with the trolley lines 27, the circuit through motor 17 will be closed as follows: From motor 17 through wire 28, trolley wires 27 and trolley 36, to wire 30, lower section of contact ring 20

brush 21, contact ring 19 and wire 33 and battery 34, back to said motor. This, of course, starts the motor 17 into action and the motor being started into action will, through the eccentric 8 and other mechanical connections described, move the switch from 90

its normal position, shown in Fig. 1, into its side track position shown in Fig. 3. Otherwise stated, half rotation of the said eccentric 8 will accomplish the above result and at 95

the completion of this half rotation of the said eccentric, the brush 21 moving in the direction of the arrow marked on Fig. 1, will pass from the lower ring section 20 with which it is engaged in Fig. 1, into engagement with the upper ring section 20, as 100

shown by dotted lines in Fig. 1. When this half rotation of the said crank is completed, the motor is stopped for the following reasons: The locomotive immediately in passing 105

toward the switch, beyond the track contact 22, short circuits battery 25 and thereby de-energizes the magnet 26 and causes the contact lever 29 to drop out of engagement with the contact 32, so that when the contact brush 21 is moved into engagement with the 110

upper section 20, the circuit through the motor 17 is again opened, the motor being stopped, and the switch returned to its normal position, as shown in Fig. 1. When this 115

half rotation of the said crank is completed, the motor is stopped for the following reasons: The locomotive immediately in passing 120

toward the switch, beyond the track contact 22, short circuits battery 25 and thereby de-energizes the magnet 26 and causes the contact lever 29 to drop out of engagement with the contact 32, so that when the contact brush 21 is moved into engagement with the 125

upper section of the contact ring 20, as shown by dotted lines in Fig. 1, the battery circuit to the motor 17 is not closed. When the brush 21, however, is left in the dotted line position, Fig. 1, it stands in such position that when the rear end of the train passes onto the side track, beyond the track insulations 24, the battery 25 will be no longer short-circuited, but its circuit will be closed through the magnet 26 and the switch lever 29 will be again raised into an engagement with the contact 32. This action just noted, again closes the battery circuit 34 through the motor 17 and causes the motor 15 to move until it has again returned to contact 21 and the full line position shown in Fig. 1, and thereby reestablishes normal main line connections, with the switch again restored to normal position, or in position 20 to render the main line operative.

This improved switch actuating mechanism materially reduces the time factor required in taking sidings, decreases the fuel consideration which would, with ordinary 25 switch mechanism, be required in starting and stopping a train at sidings, and furthermore, materially reduces breaking in two of trains and the wear and tear of brake apparatus, draft rigging, and other parts of the 30 equipment.

The switch mechanism in the drawings is shown as arranged only for automatic control in running the train from the main line onto a siding or switch track, but it is, of 35 course, obvious, that it might be also reversely arranged to automatically control the movement of trains from a siding onto a main line.

What I claim is:

40 1. An electric switch actuating mechanism comprising a "to and fro" switch throwing device, a motor for operating said switch throwing device, and a motor controlling circuit including terminal trolley lines, both 45 independent of the rails.

2. An electrical switch actuating mechanism comprising a "to and fro" switch throwing device, a continuous direction motor for operating said switch throwing device, and electric motor actuating connections and coöperating devices arranged to 50 close the motor circuit on the approach side of the switch and cause the said motor to move the switch throwing device in one direction, and arranged to automatically close 55 said motor circuit on the other side of said switch and cause said motor to again operate in the same direction and impart the reverse switch operating movement to said switch 60 throwing device.

3. The combination with the rails of a main line, branch line and coöperating switch arranged in an insulated track section and connected to a source of electrical 65 energy, of a "to and fro" switch throwing

device, a continuous direction motor for operating said switch throwing device, and electric circuit connections including said motor and a source of electrical energy, and comprising terminal trolley lines and a circuit selector. 70

4. The combination with the rails of a main line, branch line and coöperating switch arranged in an insulated track section and connected to a source of electrical 75 energy, of a "to and fro" switch throwing device, a continuous direction motor for operating said switch throwing device, electric circuit connections including said motor, a source of electrical energy, terminal trolley 80 lines, a circuit closer, a magnet normally holding said circuit closer in a circuit closing position and itself connected across the branch line rails, and a source of electrical energy connected across the main line rails. 85

5. The combination with the rails of a main line, branch line and coöperating switch arranged in an insulated track section, of a source of electrical energy connected across the approach ends of the insulated 90 section of the main line, a magnet connected across the branch line rails of said insulated section, a "to and fro" switch throwing device, a continuous direction motor for operating said switch throwing device, a circuit 95 selector including continuous and sectional contacts and a coöperating brush, which brush receives movement from said motor, terminal trolley lines extended a limited distance along the track rails, a source of electrical energy connected to the continuous contact of said circuit selector and to one side of said motor, a lead connecting one of the said trolley lines to the other side of said motor and to one of the contact sections of 100 said circuit selector, a circuit closer in the latter noted lead between said motor and sectional contact, which circuit closer is normally held closed by said magnet, and another lead connecting the other trolley line 110 to the other sectional contact of said circuit selector.

6. The combination with the rails of a main line, branch line and coöperating switch, arranged in an insulated track section and connected to a source of electrical 115 energy, of a "to and fro" switch throwing device, a motor for operating said switch throwing device, and electric circuit connections including said motor, and a source 120 of electrical energy, and comprising terminal trolley lines that are independent of the track rails and extend parallel thereto.

7. The combination with the rails of a main line, branch line, and coöperating 125 switch arranged in an insulated track section connected to a source of electrical energy, of a "to and fro" switch throwing device, a motor for operating said switch throwing device, electric circuit connections 130

including said motor, a source of electrical energy and terminal trolley lines extended along the main line rails, and a magnet normally holding said circuit closed and itself connected across the branch line rails.

8. The combination with the rails of a main line, branch line and coöperating switch, arranged in an insulated track section of a "to and fro" switch throwing device, a continuous direction motor for operating said switch throwing device, electric circuit connection including said motor, a source of electrical energy and terminal trolley lines extended along to the main line rails, a magnet normally holding said circuit closed, and itself connected across the branch line rails, a source of electrical energy connected across the main line rails, and a circuit closer engageable with said terminal trolley lines to close the circuit on approaching a switch.

9. The combination with the rails of a main line, branch line and coöperating switch, arranged in an insulated track section and connected to a source of electrical energy, of a "to and fro" switch throwing device, a motor for operating said switch throwing device, an electric circuit selector connected to and controlling said motor, separated terminal trolley lines extended along the main line approach to the switch, one of said trolley lines being connected to one side of said circuit selector, and the other being connected to the other side of said circuit selector, through a circuit closer, and being also connected to said motor, and a magnet connected across the switch line rails and normally holding said circuit closer in a circuit closing position.

10. The combination with the rails of a main line, branch line and coöperating switch arranged in an insulated track section and connected to a source of electrical energy, of a "to and fro" switch throwing device, a motor for operating said switch throwing device, an electric circuit selector connected to and controlling said motor, separated terminal trolley lines extended along the main line approach to the switch, one of said trolley lines being connected to one side of said circuit selector, and the other being connected to the other side of said circuit selector, through a circuit closer, and being also connected to said motor, and a magnet connected across the switch line rails and normally holding said circuit closer in a circuit closing position, the said circuit selector comprising a continuous and a sectional contact ring and a motor driven contact engageable therewith.

11. The combination with the rails of a main line, branch line and coöperating

switch arranged in an insulated track section of a "to and fro" switch throwing device, a continuous direction motor for operating said switch throwing device, a motor controlling circuit selector comprising a continuous and a sectional contact ring and a motor-driven contact coöperating therewith, of terminal trolley lines extending along the main line switch approach, one of the said trolley lines being connected to one side of the sectional selector ring, and the other trolley line being connected to said motor and being also connected to the other side of the sectional ring of said selector, through a circuit closer, a magnet connected across the side track rails and normally holding said circuit maker closed, and a source of electrical energy connected across the main line rails.

12. The combination with the rails of a main line and branch line and a track switch coöperating therewith, all arranged in an insulated track section and connected to a source of electrical energy, of an electric motor for operating said track switch, and electric circuit connections for controlling said motor, including a source of electrical energy, a circuit selector, terminal trolley lines connected to said source of electrical energy, through said circuit selector, an electric switch connected to said source of electrical energy, through said circuit selector, and a magnet connected across the branch line and normally holding said electric switch in a closed position.

13. The combination with the rails of a main line and branch line and a coöperating switch, of electrically actuated means independent of said track rails, for operating said switch in one direction, on approach of a train, and electrically actuated means, including said rails and certain of the parts of said first noted means, for operating said switch in the other direction, after the train has passed said switch.

14. The combination with the rails of a main line and branch line and coöperating switch, of electrically actuated means independent of the track rails, including a source of electrical energy, a motor, and a circuit selector operative to move the switch in one direction on approach of a train, and electrically actuated means including said motor, said circuit selector, and track rails, for operating said switch in the other direction, after the train has passed said switch.

In testimony whereof I affix my signature in presence of two witnesses.
